UNITED STATES PATENT OFFICE

2,418,915

ADJUSTABLE SHOWER DEVICE

Vladimir K. Volk, Saginaw, Mich.

Application November 30, 1944, Serial No. 565,841

1 Claim. (Cl. 4—145)

1

My present invention, in its broad aspect, has reference to improvements in adjustable shower baths which may be installed wherever there are hot and cold water facilities available and a waste water outlet, as for instance, a toilet comprising a closet bowl with waste connections. My invention enables a shower-bath to be installed over a toilet to utilize the waste water disposal facilities of the toilet for the purpose of draining waste water from the shower-bath basin or floor, and to utilize the hot and cold water-supply facilities of a hand basin adjacent the toilet for furnishing water to the shower-bath, and the tubular supports for the shower curtain may be adapted to be used as hot and cold water connections to the shower head. The frame of the cabinet (which may be designed for supporting curtains or the like) is preferably adjustable, and the shower floor is shiftable so as to be disposed over a toilet bowl or the like or removed therefrom. The shower head is adapted to be connected with any suitable water supply such as the tubular frame to receive hot and cold water, and the shower floor is provided with hooks or other appropriate fastening means to support the floor removably or shiftable on the frame. Swingable or rotating step devices are provided for stepping up to the shower floor. From the foregoing, it will be seen that I have provided a shower device which is not only adjustable in size, but can be set up where both shower bath and closet bowl facilities would otherwise not be expedient or available. Furthermore, the construction is such that the tubing of the shower frame may be used for hot and cold water service connections, and the frame is sturdy, simple and relatively inexpensive to manufacture and install. The outlet of the shower-bath floor utilizes the ordinary waste connections of the toilet bowl for disposal of shower-bath drainage.

Other and equally important objects and advantages of my invention will be apparent from the following detailed description and drawings, but it is pointed out that changes may be made in form, size, shape, construction and arrangement of parts, without departing from my broad inventive concept or the scope of the appended claim.

In the drawings wherein I have illustrated a preferred form of my invention:

Figure 1 is a front elevation of my device;

Figure 2 is a side view;

Figure 3 is a top plan view;

Figure 4 is a transverse section taken on the line 4—4 of Figure 2.

2

Figure 5 is a detailed, fragmentary view, partly in section, showing the water inlet connection, the connection for a support for the shower floor, and a view of one of the swingable steps:

5 Figure 6 is a section on the line 6—6 of Figure 5, and shows the pin for holding the step in adjusted position;

Figure 7 is a view of the step lifted from engagement with the pin to be swung out of the way, and

10 Figure 8 is a section on the line 8—8 of Figure 2.

In the drawings wherein like characters of reference are used to designate like or similar parts throughout the several views:

15 The numeral 1 designates a conventional toilet installation having a flush tank 2 and a bowl 3 with a cover 4, and 5 is a part of a hand basin or the like having a water connection 6. Any hot and cold water connections will suffice for my device, and one is shown in detail in Figure 5. The above parts are conventional installations and form no part of my invention.

20 My shower bath frame construction preferably includes four vertical frame members 7. These may be tubular, and, to save pipe and plumbing, 25 one may be utilized as a hot water inlet and the other as a cold water inlet, or a connection 6 may be tapped into a coupling 8—see Figure 5—with a frame member 7 joined to the outlet so that tempered water from the supply pipes of

30 the hand basin is led directly to the shower bath.

25 Each vertical frame member 7 has a foot 9 at its lower end, and a rectangular tubular frame at the top, formed with sectional tubular side bars 10 coupled by threaded sleeves 11 for adjustment, 35 and the side bars 10 and 12 are joined by pipe fittings 13 to the tops of the vertical members 7. A length of tubing 14 is connected by a T 15 to one of the bars 12 to receive water, and deliver to the adjustable shower head 16. The curtain 40 17 is hung by suitable rings 18 on the bars 10 and 12. Valves 19 and 20 may be provided in the vertical frame members 7 to regulate the flow of water to the shower head 16.

35 The vertical frame members are placed around the toilet installation 1. Lower frame members 21 are provided slightly higher than the closet bowl 3 to present a preferable supporting means for the floor of the shower-bath while in a substantially horizontal position. The rear member 50 21 has adjustable sections joined by a threaded sleeve 22. Shower floor 23 has fastening means such as hooked cross bars 24 to releasably keep the floor in position on its support. Bars 24 are removably engaged over members 21 and the shower

55 floor is placed thereon with its drainage outlet

25 communicating with bowl 3. Conveniently located on the vertical frame members 7 are swingable steps 26. Each step has a tubular enlargement or base 27 which is slotted at 28 to engage a pin 29 on the frame member, so that when the step is swung out as in Figure 5, it engages the pin to be firmly held in place. To swing the steps back under the bowl 3, they are lifted out of engagement with the pins 29 as in Figure 7 and swung back. The shower floor 23 is removable and may be shifted clear of the bowl when not in use, in which case the shower frame and curtain arrangement serve to enclose the toilet installation. Flexible connections may be used in place of pipe connections to the water supply.

I claim:

A shower device for use with a toilet installation and water service connections, comprising vertical and horizontal supporting members, enclosing a toilet bowl, a shower receptor carried by said horizontal members above the toilet bowl and having an outlet connection into the bowl; a pair of hooked cross bars secured to said receptor at two opposite sides thereof and adapted

5 to releasably hook over said oppositely situated horizontal members so as to permit, at will, the disengagement and bodily removal of the receptor from the frame and toilet installation; or to permit hinge action between the hooked cross bars at either side of said receptor and a corresponding horizontal frame member engaged thereby.
